UNITED STATES PATENT OFFICE.

WILLARD C. AVERILL, JR., OF HOUSTON, TEXAS.

PROCESS FOR SEPARATING HYDROCARBONS.

Original application filed October 7, 1922, Serial No. 593,084. Divided and this application filed December 19, 1923. Serial No. 670,646.

To all whom it may concern:

Be it known that I, WILLARD C. AVERILL, Jr., a citizen of the United States of America, and a resident of Houston, county of Harris, State of Texas, have invented certain new and useful Improvements in Processes for Separating Hydrocarbons, of which the following is a description.

The present application is a division of 10 my pending application, Serial No. 593,084, filed October 7, 1922.

An object of my invention is to obtain a clean separation of low boiling hydrocarbons from high boiling hydrocarbons both 15 economically and rapidly.

A second object of my invention is to obtain an additional refining of the low boiling point hydrocarbons simultaneously with their separation from the high boiling point 20 hydrocarbons.

The novel features of my process are pointed out with particularity in the appended claims. The invention itself, however, with further objects and advantages, 25 will best be understood by reference to the following description, taken in connection with the accompanying drawing in which—

The figure is a schematic representation, partly in section of apparatus for carrying 30 out my invention.

In the drawing 1 indicates a still into which crude petroleum or like oil is introduced by pump 1^a, through pipe 1^b. Preferably the pipe 1 is coiled within the 35 still below the oil level therein so that the incoming oil is heated approximately to the temperature of the oil in the still before being discharged from the pipe. The oil is supplied from the pipe 1^b into pans 2 under pressure sufficient to prevent the water 40 in the oil changing into steam within the pipe 1^b. The upper portion of the pipe 1^b is perforated as indicated and the water consequently suddenly vaporized into steam 45 above the pans 2, atomizing the oil, and assisting in the liberation of gasoline and like low boiling ingredients of the hydrocarbon being distilled. Separation of steam and light hydrocarbons from heavy hydrocarbons is further promoted by the pans 50 2 into which the unvaporized hydrocarbons fall from the pipe 1^b and from which they continue to overflow from one to the other

until they unite with the body of liquid in the lower part of the still.

Vapors of the hydrocarbons of the desired specific gravity and above a definite vaporization point being distilled off, together with water vapor, pass out of the still 1, through a large upwardly inclined pipe 3 which delivers the vapors into a towerlike dephlegmator 4, which may be packed with any suitable material such as broken coke, bricks, stoneware, or the like. In practice, I have found it desirable to use 65 a plurality of small iron pipe sections 4^a arranged within the dephlegmator as shown.

A portion of the hydrocarbon vapor condenses in tower 4 and drops to the bottom of the tower accompanied by the condensed water vapors. At the bottom of the tower 4 is a water draw-off leg 5 with an automatic drain trap 5^a having a vent 5^b, drain 5^c acting to allow the water to be discharged continuously. From the top of the draw-off leg 5, where the intrapped liquid hydrocarbons float a pipe 6 leads off to circulate pump 6^a which pumps the hydrocarbon condensate through spray 7 at the top of the tower 4. This condensate then comes into contact with the ascending vapors which has the effect of reheating and removing from the condensate practically all remaining high boiling oils or heavy ends. This operation is continuous and by means of 85 the circulating pump the oil is exposed many times to the ascending vapors and an excellent separation of high boiling point material or heavy ends from low boiling point material or light ends is obtained. I regard 90 as the important feature, and to which I attribute the success of my invention, the fact that the condensate is repeatedly sprayed over and subjected to the action of the rising vapors. Heretofore, the practice has been to allow the condensate to come into contact with the rising vapors to collect the heavy ends so that they may be returned to the still. On the contrary in 95 my apparatus the vapors from the still pass through the falling condensate repeatedly after separation from the water so that when the vapors leave the upper ends of the dephlegmator 4, they carry substantially all 100 of the lighter hydrocarbons which the original oil contained. This had been found

to increase the production of gasoline obtained from Mexican oils by approximately 50 per cent. In dephlegmator 4, the rising vapors are indicated by the arrows A and 5 the circulated condensate by the streams B from the spray 7.

Uncondensed vapors are led off from the upper part of tower 4 and delivered into the lower part of a second tower 8 by means 10 of pipe 8^a. Tower 8 is also preferably packed with material inert to the hydrocarbon and steam vapors, such as that mentioned in connection with tower 4. From the lower part of tower 8, a pipe 9 leads 15 to the lower part of tower 4, this pipe 9 inclining downwardly from tower 8 to tower 4 whereby condensed hydrocarbons are back trapped through pipe 9 to tower 4. The condensate from tower 8 is then circulated 20 through the tower 4 by pump 6^a along with the condensate from tower 4. Tower 8 may also have a spray 10 in its upper portion whereby water may be introduced at the top of tower 8 for regulating the temperature. 25 This, however, is not always necessary, except in very hot weather, as the radiation from the tower 8 is found sufficient to carry off the surplus heat. Water is removed from the bottom of tower 8 through draw-off leg 30 11 and overflow pipe 11^a, this pipe having a vent 11^b.

Hydrocarbon or oil vapors are removed from the upper part of tower 8 through pipe 12 and may be condensed in a condenser 13.

35 By regulating the speed of the circulating pump 6^a and assuming a substantially constant water temperature, the amount of water supplied through sprayer 10, a distillate of any desired end point results.

40 The very heavy condensates which are separated out flow back through vapor line or pipe 3 to the still, the pipe 3 being inclined downwardly from the tower 4 to the still in order to permit the heavy liquid to 45 thus flow back.

High boiling liquid residue is removed from still 1 through pipe 14, having vent 14^a, the pump 15 drawing off the liquid it is desired to remove through pipe 14.

50 The effect of my invention is that a very excellent separation of gasoline is obtained at one operation, whereas ordinarily two distillations are necessary. I am thus able to save the expense and material losses which 55 naturally result from two distillations as compared with one. My invention is also applicable to either light or heavy oils, and any desired cut can be obtained, with sharp separation, as indicated above.

60 While I have illustrated and described the preferred embodiment of my invention and the preferred method of operating the same, I do not wish to be limited to details 65 of construction, arrangement or operation herein disclosed, except in so far as such de-

tails are essential to the novelty of the appended claims.

What I claim and desire to protect by Letters Patent is:

1. The method of obtaining light hydro- 70 carbons from hydrocarbon oils containing water, which comprises vaporizing the oil to be treated, partially condensing the hydrocarbon vapors and simultaneously condensing the water vapors, subjecting the 75 remaining vapors thereof to previously condensed hydrocarbons of higher boiling point obtained from said vapors, which latter are supplied by removing the water collected from the condensed vapors, and continuously 80 circulating through said vapors the hydrocarbons thus obtained.

2. The method of obtaining light hydro- 85 carbons from hydrocarbon oils containing water, which comprises vaporizing the oil to be treated, continuously subjecting the hydrocarbon vapors thereof to previously condensed hydrocarbons of higher boiling point obtained from said vapors whereby 90 heavier portions of said hydrocarbon vapors and said water vapors are collected as condensates, separating said water from said hydrocarbon condensate.

3. The method of obtaining light hydro- 95 carbons from hydrocarbon oils containing water, which comprises vaporizing the oil to be treated, partially condensing the hydrocarbon vapors and simultaneously condensing the water vapors, subjecting the 100 remaining vapors thereby formed to previously condensed hydrocarbons of higher boiling point obtained from said vapors, which latter are supplied by removing the water collected from said condensed vapors, continuously 105 circulating through said vapors, the hydrocarbons thus obtained, and then removing the remaining heavier hydrocarbons from the vapors thus obtained by partially cooling the same.

4. The method of obtaining light hydro- 110 carbons from petroleum oils containing water, which comprises vaporizing the oil to be treated, partially condensing the hydrocarbon vapors and simultaneously condensing the water vapor obtained from said 115 vapors whereby heavier portions of said vapors and said water are collected as condensates, separating said water from said hydrocarbon condensate, continuously subjecting said vapors to the condensate separated from said water, and then removing the remaining heavier hydrocarbons from the vapors thus obtained by partially cooling said vapors by subjecting the same to contact with water at a predetermined temperature.

5. The method of treating a mixture of relatively high and relatively low boiling hydrocarbon vapors which consists in as a 130 first step, vaporizing the oil to be treated,

partially condensing said vapors, separating the condensed vapors therefrom, repeatedly spraying the hydrocarbon condensate through the untreated vapors of said mixture, thereafter returning a portion of the condensate thus obtained to the vaporizing source of said mixture, removing the uncondensed vapors; as a second step in further partially condensing said uncondensed vapors by spraying with water at a definite 10 temperature, removing the remaining uncondensed vapors, separating the water from the condensate, removing the condensate and returning it to the first mentioned condensate; and as a third step, in condensing 15 the remaining uncondensed vapors.

WILLARD C. AVERILL, JR.
